UNITED STATES PATENT OFFICE

115,728

DESIGN FOR A COMB HOLDER RACK

Nicholas J. Bardaville, Lansing, Mich.

Application July 14, 1938, Serial No. 78,481

Term of patent 3½ years

To all whom it may concern:

Be it known that I, Nicholas J. Bardaville, a citizen of the United States, residing at Lansing, in the county of Ingham and State of Michigan, have invented a new, original, and ornamental Design for Comb Holder Racks, of which the following is a specification, reference being had to the accompanying drawing, forming part thereof.

In the drawing:

Fig. 1 is a front elevational view of the comb holder rack, showing my new design.

Fig. 2 is a side elevational view.

Fig. 3 is a vertical sectional view, taken along line 3—3 of Fig. 1.

I claim:

The ornamental design for a comb holder rack, as shown.

NICHOLAS J. BARDAVILLE.
